(57) **CLAIM**

The ornamental design for transparent drinking vessel, as shown and described.

DESCRIPTION

FIG. 1 is an isometric view of a transparent drinking vessel of the design;

FIG. 2 is front elevation view of the design of the transparent drinking vessel shown in FIG. 1;

FIG. 3 is a top plan view of the design of the transparent drinking vessel shown in FIG. 1; and,

FIG. 4 is a bottom plan view of the design of the transparent drinking vessel shown in FIG. 1.

The broken lines represent portions of the transparent drinking vessel that form no part of the claimed design.
